UNITED STATES PATENT OFFICE

2,458,271

ROTATING BASE FOR LOAD HANDLING MACHINES

William M. Huston, Lima, Ohio

Application July 5, 1945, Serial No. 603,382

13 Claims. (Cl. 212—59)

1

This invention relates to load handling machines and is particularly concerned with a rotating base structure adapted to be mounted for swing motion on a crawler truck.

The invention is especially concerned with a rotating base structure for load handling machines of large size capable of handling heavy loads, to which end of rotating base of this invention incorporates a novel arrangement of primary structural elements, bracing webbing, and the like, having adequate strength to withstand the heavy loads and forces encountered in a large and heavy machine, such, for example, as the heavy loads imposed on the base structure by the operation of the machinery carried on the base, as well as by the boom itself which is mounted on the base.

According to the invention, the rotating base structure, including both the base proper and also certain other parts which are directly and rigidly connected therewith, such as the machinery frames, are arranged to constitute a firm foundation or "backbone" for the boom, gantry, counterweight, power plant, operating machinery, and cab structure all of which are mounted on the base, the base, in turn, being mounted to rotate on the supporting truck structure about the axis of swing motion.

One of the more specific objects of the invention is a novel arrangement of structural elements in the base, providing a pair of pockets in the base structure itself adapted to receive and mount a pair of cable drums employed for boom hoist. In the arrangement of the invention the pockets for receiving the boom hoist drums are divided from each other by a structural member which serves also in the support of a power shaft from which power is transmissible to the boom hoist drums which are mounted in the pockets.

Another feature of the invention involves a novel arrangement of structural parts adapted to the support of specially formed fittings to which both the boom and the gantry are connected.

Still another object of the invention is the provision of a rotating base structure having a pocket or recess therein adapted to receive certain operating gearing, together with a gear casing of novel arrangement, the casing being sectionalized in a special manner providing convenience in handling and mounting of the casing sections.

According to the invention the gear casing above mentioned is further arranged to provide

2

support for certain other devices thereabove, as will further appear.

Still another aspect of the invention is the provision of various mounting pads on the base structure itself, providing for the support of mounting and controlling devices associated with the machinery carried by the rotating base. A more or less specific feature to be noted in this connection is the arrangement of portions of the base structure at the upper and lower sides thereof adjacent a given region, which portions are adapted to cooperate, respectively, in the support of a brake for an operating unit of the machine and with a controlling unit for said brake, the base structure being apertured in this region so as to pass a brake control connection.

How the foregoing and other objects and advantages are attained will appear more fully from the following description referring to the accompanying drawings in which—

Figure 1 is a top plan view of a rotating base casting incorporating various features of the invention;

Figure 2 is a bottom plan view of the base structure shown in Figure 1;

Figure 3 is a side elevational view of the rotating base shown in Figures 1 and 2, with various machinery frames and supports mounted thereon;

Figure 4 is a longitudinal vertical section through the structure shown in Figure 1, taken as indicated by the line 4—4 on Figure 1, this view also indicating the location of certain units of the operating machinery mounted on the base;

Figure 5 is a transverse sectional view taken as indicated by the line 5—5 on Figure 1;

Figure 6 is a transverse sectional view taken as indicated by the line 6—6 on Figure 1;

Figure 7 is a transverse sectional view taken as indicated by the line 7—7 on Figure 1 but further indicating the location and arrangement of certain of the machinery supports and machinery shafts which are carried on the base;

Figure 8 is an enlarged top plan view showing a portion only of the base structure shown in Figure 1, and illustrating certain gear casing parts mounted thereon; and

Figure 9 is a side elevational view of the structure shown in Figure 8.

Although the drawings illustrate a base structure in the form of a casting, it is to be understood that at least most features of the invention may be attained in a built-up type of structure, for instance a structure fabricated by weld-

ing together various plates, beams, webbing, etc.

The structure shown in the drawings includes transversely spaced longitudinally extending primary structural elements 12-12 which are extended along the sides of the base throughout the length thereof. An interbracing plate or deck 13 extends between the upper edges of the elements 12. The parts 12 and 13 are braced and interconnected by various webbing and the like, including certain webs specifically referred to hereinafter.

In a position transversely centered, but located well forwardly of the base, a bearing supporting housing 14 is provided to cooperate in the support of the vertical propel shaft 15 (see Figure 4) which serves not only to transmit driving power to the crawler truck on which the base is mounted but also to define the axis of swing motion of the base with respect to the truck. The housing 14 is transversely braced by webbing 16-16 (see Figure 2) and also by centrally disposed longitudinally extending webbing 17 and 18.

Another bearing receiving housing 19 is located in the base rearwardly of the housing 14, this housing cooperating in the support of the vertical swing shaft 20, carrying a pinion 21, adapted to cooperate with an internal ring gear arranged in association with the truck structure, for instance in the manner disclosed in copending application Serial No. 603,376, filed concurrently herewith, entitled Load handling machines.

Still another bearing housing 22 is arranged in the base structure to the rear of the housing 19, this housing cooperating in the support of a shaft 23 from which power is transmissible alternatively to shafts 20 and 15 through gearing 24, 25 and 26, the gears 25 and 26 being adapted to be clutched, respectively, to the shafts 20 and 15 on which they are mounted. The details of this form of drive mechanism need not be considered herein, since the same form no part of the present invention per se and are, in any event, fully disclosed in the copending application above mentioned. Certain features of this arrangement further appear in issued Patent No. 2,354,863, August 1, 1944. The bearing housing 19 is braced by the central webbing 18 and also by webbing 27 which extends rearwardly therefrom to join the housing 22, which latter housing is further braced by central webbing 28 extended rearwardly therefrom (see particularly Figures 2, 5 and 6).

Machinery frames 29 and 30 are mounted on the base structure itself near the edges thereof, the frames being extended fore-and-aft throughout a large portion of the length of the base. Each frame is provided with a footing 31 providing flanges extended at both sides of the lower edge thereof, adapted to rest on elongated supporting pads 32, the flanges being secured to the pads by bolts and preferably also by welding, so as to firmly anchor the machinery frames to the base structure proper. The machinery frames, as best seen in Figure 3, are provided with recesses and apertures such as indicated at 33, 34 and 35, to provide for the support of the primary machinery shafts, especially drum shafts for hoisting and for other functions, depending upon the particular type of machine in which the structure is used. It may here be mentioned that the structure of the present invention is well adapted to cranes, for instance in the form disclosed in the copending application above referred to, and also to shovels, drag lines, clam shells and the like.

For transverse bracing, the machinery frames 29 and 30 are interconnected at their upper edges by a brace 29a (see Figure 3). Supports 29c are adapted to be mounted on the machinery frames 5 and serve to carry portions of the cab structure which is mounted on the base to enclose the operating machinery.

The footing or flanges 31 of the machinery frames are interbraced with the upright portions 10 of the frames themselves by means of webbing 36 (see Figures 3 and 7). Toward the front ends thereof of the machinery frames are provided with extensions 37 which serve to contribute additional strength to the base structure adjacent the forward end thereof (at which point the boom and gantry are connected) and which may further be employed for the mounting of other machinery which need not be considered herein.

In front of the machinery frames, adjacent each forward corner, the base is provided with pads 38 adapted to support separately formed devices 39 for mounting the foot of the boom and also the lower forward ends of the front or compression gantry legs. Each of these devices 20 may, if desired, be fabricated or, as shown in the drawings, may comprise a casting consisting of a bottom wall 39a adapted to rest on the pad 38, and upright walls forming pockets 40 and 41 in the rear portion thereof and forming 25 spaced and apertured lugs such as indicated at 42 projecting forwardly. The lugs 42 cooperate with a pin 43 serving to mount the boom 44. The forward lower ends of the front or compression 30 gantry legs (a fragment of one of which is shown at 45) are adapted to be received in pockets such as those indicated by the numeral 41, each leg being secured in position by a pin 46. The unitary formation of these mounting devices 39 is of advantage in insuring adequate strength to transmit 35 heavy forces between the gantry and boom during operation. The devices 39 are advantageously both bolted and welded to the base structure itself and are also desirably welded to the front ends of the extensions 37 of the 40 machinery frames and in this way a structure of substantial depth and strength is provided toward the front end of the rotating base. With 45 respect to the mounting of the devices 39, further attention is directed to the fact that extensions 50 47 are provided at the front of the rotating base so as to extend the area of support and provide for additional bracing by webbing 48 which lies in longitudinal vertical planes and interconnects the extensions 47 with the transverse structural 55 element 49 of the base structure.

At the forward end of the base, a fair-lead bracket 50 is provided intermediate the extensions 47 in the region of the central longitudinal bracing element 17 (see Figure 2). The fair-lead bracket is adapted to cooperate with a fair-lead as used in a drag line or other similar load handling machine, in which a heavy pull longitudinally of the machine is required. The positioning of the bracket as described above and the provision of the longitudinal element 17 is of importance in carrying the heavy loads encountered in the operation of the fair-lead.

On the underside of the base, as shown in Figure 2, pads are provided as indicated at 51, 52, 70 53 and 54, to provide for the mounting of brackets for supporting main and hook rollers which are adapted to ride on the circular track of the truck of the machine, a pair of the main rollers being indicated in Figure 2 at 51a. The arrangement 75 and mounting of these rollers need not be con-

sidered in detail herein as they form no part of the present invention per se. However, they are fully disclosed in the copending application Serial No. 603,379, filed concurrently herewith and entitled Load handling equipment. It is here pointed out that some of the heaviest loads required to be transmitted through the rollers to the truck structure of the machine are those carried from the rotating base through the hook rollers which are offset to the rear of the center of swing motion. The pads 54 above mentioned provide for the support of the hook rollers just mentioned, and for the purpose of insuring firm fastening of the mounting brackets for these rollers, bolt holes 55 are provided through the base structure itself (see Figures 1 and 2), the bolt holes being counterbored toward their upper ends as indicated at 56 (see Figure 1), so that the heads of the fastening bolts will lie below the machinery frames and other parts mounted on the top of the base structure. The various pads 51 to 54 are supported and braced by webbing such as indicated at 51 in Figure 2, so as effectively to carry the roller loads.

As best seen in Figure 4, longitudinally spaced transversely extending structural elements 58 and 59 are arranged toward the rear of the base structure, being interconnected with the primary longitudinal side elements 12-12. In this region, an additional longitudinally extending element 60 is provided to interconnect the elements 58 and 59. The interbrace 60 (see Figures 1 and 2) is offset toward one side of the longitudinal vertical mid-plane of the bearing housings 14, 19 and 22, so as to divide the space between the transverse elements 58 and 59 into two pockets 61 and 62, one of which is of substantially greater transverse dimension than the other. These pockets are adapted to receive the boom hoist drums shown in Figure 7 at 63 and 64 which are mounted to rotate on the boom hoist shaft 65 which is supported in the side portions of the base structure. The larger pocket 62 is adapted also to accommodate a transmission unit 66 through which power is transmissible to the boom hoist drums 63 and 64. This arrangement of boom hoist drums and of the drive therefor is disclosed in copending application above identified, Serial No. 603,376, entitled Load handling machines, and need not be considered in detail herein. It is here noted, however, that the transmission unit 66 is provided with mounting flanges 66a and 66b (see Figure 4) which are adapted to be secured to the supporting pads 67 and 68, respectively, which are arranged in the regions of the transverse structural elements 59 and 58, respectively.

The longitudinally extending interbrace 60 also serves to carry a mounting pad 69 adapted to support the standard 70 (see Figure 7) which cooperates in mounting the power or jack shaft 71. Power is transmissible from the jack shaft to the transmission unit 66 in a manner which need not be considered in detail herein. It is noted, however, that the shaft 71 is adapted to receive power through the sprocket 72, the sprocket being coupled by means of a chain to an engine (not shown). The jack shaft 71 further receives support from the machinery frame 30, as well as from an additional standard 73 which lies between the plane of the sprocket 72 and the gearing 74 through which power is transmitted from the jack shaft to other machinery shafts mounted on the frames 29 and 30. One such additional shaft is shown in Figure 7 at 75.

Referring again to Figures 1 to 4 inclusive, it

will be noted that at the rear of the rotating base the side portions thereof are extended rearwardly as at 76-76 to provide for the support of counterweight, as shown at 77 in Figure 3, and also for the support of the power plant or engine. The operating machinery through which driving of the shaft 23 (in the mid-region of the base) is effected, forms no part of the present invention per se, but attention is now called to the fact that the gearing 24, 25 and 26 which is associated with vertical shafts 23, 20 and 15, is located in a recess or pocket formed in the upper side of the base structure, being defined by bottom and side walls 78 and 79, as best shown in Figure 4. This pocket 15 serves as a lubricant reservoir for the gearing therein and the shafts on which the several gears are mounted.

As shown in Figure 1 a pad 80 surrounds the upper edge of the pocket mentioned just above to provide for the mounting of a gear casing, the arrangement of which is best shown in Figures 8 and 9. As there seen, the gear casing is sectionalized, comprising three principal sections 81, 82 and 83. The dividing lines between the sections extend transversely of the machine, as at 84 and 85, these dividing lines further being so located longitudinally of the base that section 81 overlies the region of gear 26, section 82 overlies the region of gear 25 and section 83 overlies the region of gear 24.

Bevel gear 86 is fixed at the upper end of vertical shaft 23 (see also Figure 4) and this bevel gear is housed within the casing section 83. Gear 86 is adapted to mesh with a bevel pinion 87 fixed on the transverse reversing shaft 88, the shaft 88 being adapted to be mounted in the machinery frames as at 35 (see Figure 3). Casing section 83 carries another casing part 83a having a portion 83b extended upwardly to enclose a part of the transverse reversing shaft 88. Another casing part 89, having an observation window 89a, is carried on the section 83 and is adapted to be bolted to part 83a, the part 89 serving to enclose gear 87 and also a portion of the transverse reversing shaft 88, and being adapted to be connected with a casing 29b which extends inwardly from and is formed integrally with the right-hand machinery frame 29. It may be mentioned that shaft 88 is adapted to be driven alternatively in either direction by operating machinery which need not be considered herein, although, if desired, reference may be had to copending application identified above, Serial No. 603,376, entitled Load handling machines.

By virtue of the casing arrangement described above, all of the driving gearing (87, 86, 24, 25 and 26) for the shafts 23, 20 and 15, is housed in a sectionalized casing structure the various parts of which receive at least their primary support directly from the base structure.

The casing section 81 further carries a standard 90 (see Figures 8, 9 and 3) which serves as a support for a brake band fulcrum, for instance for a hoist drum brake as disclosed in the copending application last mentioned above. A housing 91 carried by casing section 81 provides a pocket for the reception of a spring adapted to be associated with such a hoist brake. The specific manner of mounting of the brake parts in association with standard 90 and pocket 91 need not be considered herein, but attention is directed to the fact that, as shown in Figure 1, the region of the base structure underlying these parts is provided with a pad 92 of extended area, so as to provide ex-

tended supporting area for the parts mounted thereon.

Various other brackets and supports, such as those shown at 81a, 81b and 81c, are mounted on the casing part 81, these elements cooperating in the support of controlling devices for truck steering and truck locking, from which control connections are extended downwardly through opening 81d into and through the interior of the hollow vertical shaft 15 to the truck. In addition to the brackets just mentioned, casing section 81 further carries a pad 81e which is positioned to support a portion of the front wall of the cab structure.

The central section 82 of the casing carries a bracket 82a which cooperates with the control for a swing brake which is adapted to be associated with an upward extension of the swing shaft 20, as disclosed in Patent No. 2,354,863 above mentioned. Moreover, section 82 also has a central bearing housing 82b for support of the swing shaft 20.

Because of the arrangement of the several casing sections and parts above described, maximum convenience is afforded in gaining access to the gearing and in handling the casing parts when assembling and taking down the machine. It may be noted, for example, that casing section 81 may be removed independently of the mid-section 82, and further that the casing parts 83a and 89 may also be removed and replaced independently of the mid-section 82, and, moreover, independently of section 83.

From Figure 1 it will also be seen that an extended pad 93 is provided just ahead of the boom hoist drum pocket 61, this pad serving to carry a bracket 94 (see Figures 8 and 9) with which another brake band 95 is associated. Brake band 95 is adapted to be operated by a bell-crank lever 96 which in turn is actuatable by a control rod or element 97. The rod 97 may be adjusted in any desired manner, for instance by a fluid pressure power piston and cylinder device mounted at the underside of the base by means of a bracket 97a (see Figure 3). Here again, these brake operating parts need not be considered in detail, although attention is called to the provision of aperture 98 through the base (see also Figures 1 and 2), so as to accommodate the control connection (bell-crank lever 96) which extends from the control device mounted below the base to the brake band above the base.

With further reference to Figure 1 it will be noted that supporting pads 99 and 100 are provided on the base adjacent the front end thereof intermediate the planes in which the machinery frames are mounted. These additional pads may be employed for supporting other machinery units; for instance, the pad 99 may be used for mounting brackets adapted to carry an intermediate crowd shaft when a chain crowd is used for shovel operation, and pad 100 may be used for mounting a bracket adapted to carry a crowd chain tightener.

I claim:

1. For a crawler type load handling machine, a rotating base structure comprising a pair of primary structural elements extending longitudinally of the base in transversely spaced parallel relation, boom pivot mountings carried by the longitudinal elements adjacent the front ends thereof, longitudinally spaced transversely extending structural elements interbracing the longitudinal elements toward the rear end thereof, the base structure having means adapted to

cooperate with a vertical machinery shaft for support thereof, which means is located transversely of the base in the mid region thereof and longitudinally of the base intermediate the front end thereof and the said transverse elements, bracing webbing lying in a longitudinal vertical plane in said mid region adjacent the bearing supporting means, and bracing webbing interconnecting said transverse elements and lying in a longitudinal vertical plane laterally offset from the plane of the first webbing so as to divide the space between the transverse elements into two pockets one of which is of greater transverse dimension than the other, the smaller pocket being adapted to receive a boom hoist drum and the larger pocket being adapted to receive another boom hoist drum together with a transmission unit through which power is transmissible to the boom hoist drums.

2. In a crawler truck type load handling machine, a rotating base structure having means adapted to cooperate in the support of three vertically disposed shafts, one of which provides for truck drive and is located on the center of swing motion, a second of which provides for swing motion, and the third of which comprises a power shaft through which power is transmissible to the other two, the rotating base structure being provided with a pocket for receiving gearing for the transmission of power from the power shaft to the other two, and a casing for enclosing said gearing, the casing being removably mounted on the base structure and comprising at least two separately mounted casing sections respectively associated with said pocket in the regions of different shafts.

3. In a crawler truck type load handling machine, a rotating base structure having means adapted to cooperate in the support of three vertically disposed shafts arranged in the longitudinal vertical mid plane of the machine, one of which provides for truck drive and is located on the center of swing motion, a second of which provides for swing motion, and the third of which comprises a power shaft through which power is transmissible to the other two, the rotating base structure being provided with a pocket for receiving gearing for the transmission of power from the power shaft to the other two, and a casing for enclosing said gearing, the casing being removably mounted on the base structure and being divided along a transverse line between two of the shafts to provide a plurality of separately mountable casing sections.

4. In a crawler truck type load handling machine, a rotating base structure adapted to carry operating machinery and having means adapted to cooperate in the support of three vertically disposed shafts, one of which provides for truck drive and is located on the center of swing motion, a second of which provides for swing motion, and the third of which comprises a power shaft through which power is transmissible to the other two, the rotating base structure being provided with a pocket for receiving gearing for the transmission of power from the power shaft to the other two, and a casing for enclosing said gearing, said casing having a mounting fitting thereon adapted to cooperate in the support of a controlling device for a unit of the machinery mounted on the base.

5. In a crawler truck type load handling machine, a rotating base structure adapted to carry operating machinery and having means adapted to cooperate in the support of three

vertically disposed shafts, one of which provides for truck drive and is located on the center of swing motion, a second of which provides for swing motion, and the third of which comprises a power shaft through which power is transmissible to the other two, the rotating base structure being provided with a pocket for receiving gearing for the transmission of power from the power shaft to the other two, and a casing for enclosing said gearing, said casing being removably mounted on the base structure and comprising at least two separately mounted casing sections respectively associated with said pocket in the regions of different shafts, and a section of the casing having a mounting fitting thereon adapted to cooperate in the support of a controlling device for a unit of the machinery mounted on the base.

6. For a crawler type load handling machine, a rotating base structure adapted to carry operating machinery including a rotative operating unit having a brake associated therewith, the base having means at the upper side thereof adapted to cooperate in the support of a brake part and having means at the lower side thereof adapted to cooperate in the support of a brake controlling device, and the base further being apertured in the region of said means to pass a control connection extended from said device to the brake.

7. In a crawler truck type load handling machine, a rotating base structure adapted to carry operating machinery and having means adapted to cooperate in the support of three vertically disposed shafts, one of which provides for truck drive and is located on the center of swing motion, a second of which provides for swing motion, and the third of which comprises a power shaft through which power is transmissible to the other two, the rotating base structure being provided with a pocket for receiving gearing for the transmission of power from the power shaft to the other two, and a casing for enclosing said gearing, said casing being removably mounted on the base structure and comprising at least two separately mounted casing sections respectively associated with said pocket in the regions of different shafts, and a section of the casing having means thereon adapted to cooperate in the support of cab structure for housing the machinery mounted on the base.

8. For a crawler type load handling machine, a rotating base structure adapted to carry operating machinery including a transverse shaft mounted in spaced relation above the base, a vertical shaft and gears interconnecting said shafts; the base structure having means adapted to cooperate in supporting the vertical shaft, a gear casing part removably mounted on the base and enclosing a gear on the vertical shaft, and a second gear casing part mounted on the first and enclosing a gear on the transverse shaft.

9. For a crawler type load handling machine, a rotating base structure adapted to carry the operating machinery, gantry and boom, and a gantry and boom mounting device formed as a unit separately from the base and secured to the base, said device having upright walls forming pockets adapted to cooperate with the gantry legs in the rear portion thereof and spaced lugs projecting forwardly thereof, the walls and the lugs being apertured to receive removable connecting pins by which the gantry and boom are adapted to be removably connected with the said

device and therethrough with the rotating base structure.

10. A construction according to claim 9 in which the gantry and boom mounting device comprises a unitary casting adapted to be secured to the base structure.

11. For a crawler type load handling machine a rotating base structure adapted to carry the boom at the forward end thereof and having transversely spaced longitudinally extending primary structural elements adjacent the sides thereof, and transversely spaced machinery frames mounted on the base and rigidly connected therewith in the region of said longitudinal elements, the machinery frames having extensions in the forward region of the base projecting forwardly well beyond the main machinery-supporting portions of the frames, which extensions are also rigidly interconnected with the base in the region of said longitudinal elements to provide a combined structure of considerable overall depth so as adequately to carry the loads imposed on the rotating base by the boom.

12. A construction in accordance with claim 11 and further including separately formed devices for mounting the boom, which devices are located on the rotating base at the forward edge thereof in advance of the forward extensions of the machinery frames, and the said devices being rigidly interconnected with the rotating base and with said extensions, whereby to further contribute to the strength of the base structure in the region of mounting of the boom.

13. For a crawler type load handling machine, a rotating base structure comprising a pair of primary structural elements extending longitudinally of the base in transversely spaced parallel relation, boom pivot mountings carried by the longitudinal elements adjacent the front ends thereof, longitudinally spaced transversely extending structural elements interbracing the longitudinal elements toward the rear end thereof, an interbrace extending longitudinally of the base and inter-connecting said transverse elements, the longitudinal and transverse elements and the interbrace cooperating to define a pair of pockets in the base structure toward the rear end thereof for receiving and mounting a pair of boom hoist drums, and a pad on one of the pocket defining members adapted to carry a bearing support for a power shaft from which power is transmissible to the boom hoist drums.

WILLIAM M. HUSTON.
